UNITED STATES PATENT OFFICE

2,521,715

BATHING APPARATUS ATTACHMENT, INCLUDING CONVEYER-SUPPORTED BRUSHES FOR BATHTUBS

Wade L. Hacker, Long Beach, Calif.

Application August 24, 1946; Serial No. 692,776

2 Claims.

(Cl. 4--184)

1

This invention relates to new and useful improvements and structural refinements in a bathing apparatus and the principal object of the invention is to provide a device of the character herein described which is adapted for use in association with bath tubs, and the like, and in which a plurality of brushes, positioned upon a moving endless belt, are employed for washing the body of the user.

A further object of the invention is to provide a bathing apparatus which gains access to otherwise poorly accessible portions of the human body, such as the intermediate region of the back between the shoulder blades.

Another object of the invention is to provide a bathing apparatus which, by virtue of the construction and operation above outlined, is particularly suitable for use by persons who are physically handicapped.

An additional object of the invention is to provide a bathing apparatus which is simple in construction and operation and which, when not required, may be easily and conveniently removed from the tub with which it is used.

A still further object of the invention is to provide bathing apparatus which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is an elevational view of the invention, partially broken away to reveal its construction and positioned in situ in a bath tub;

Figure 2 is a cross sectional view, taken substantially in the plane of the line 2--2 of Figure 1;

Figure 3 is a top plan view of the invention;

Figure 4 is a fragmentary perspective view showing the mounting of one of the rollers used in the invention;

Figure 5 is a top plan view of one of the brushes;

Figure 6 is a rear elevational view of the brush shown in Figure 5;

Figure 7 is a front elevational view of said brush, and

Figure 8 is an elevational view of the atomizers used in the invention.

Like characters of reference are used to designate like parts in the specification and throughout the several views.

Referring now to the accompanying drawing

in detail, the invention embodies in its construction a tubular standard designated generally by the reference character 10, the same consisting of an upright shaft 11 supported at its lower end by means of a suitable base 12.

The upper end portion of the shaft 11 is angulated to provide a laterally extending arm 13, the same being suitably reinforced by means of a brace 14.

The free extremity of the arm 13 carries an inverted U-shaped yoke 15 the latter connecting together a pair of spaced, aligned bearing blocks 16. A shaft 17 is rotatably journaled in the blocks and carries a roller 18 which is rigidly secured thereto. One end of the shaft 17 is secured to a flexible shaft or cable 19, this extending through the tubular shaft 11 of the standard 10 and being connected at its lower end to the armature shaft of a suitable electric motor 20. The latter is mounted on the aforementioned base 12 as will be clearly apparent from the accompanying drawings and is controlled by a switch 21 provided in a convenient position on the shaft 11.

A further roller 22 is secured upon a shaft 23, this being rotatably journaled in suitable bearing blocks 24. The latter are formed on the inner surfaces of the relatively opposite side walls of a bath tub 25; whereby the shaft 23 extends transversely of the tub, as is best shown in the accompanying Figure 1. It will be noted that when the standard 10 is positioned at one side of the tub 25, the rollers 17 and 22 will be in alignment.

The shaft 23 in effect, is composed of two sections 26 and 27, these being separably connected together by a suitable coupling 28. It will be noted that by disconnecting the sections 26, 27 at the coupling 28, the shaft 23 and the associated roller 22 may be readily removed from or inserted into the bath tub.

An endless belt designated generally by the reference character 29 engages the rollers 18 and 22, the belt in effect, consisting of a pair of spaced parallel, endless straps 30, engaging annular grooves 31 formed in the lateral surfaces of the rollers 18, 22.

The belt 29 is provided at spaced intervals with a plurality of brushes designated generally by the reference character 32, these being best illustrated in the accompanying Figures 5, 6 and 7.

Each of the brushes 32 consists of a mid-section 33 and a pair of end sections 34, the latter being secured to the relatively opposite ends of the section 33 by means of suitable hinges 35. It

will be noted that the adjacent edges of the sections are beveled as at 36, whereby the sections may assume a concave formation, as is best shown in Figure 5.

The sections are retained in this formation by the resiliency of suitable springs 37, the latter assuming the form of straps of resilient material associated with the hinges 35 and adapted to normally urge the sections into the concave formation above referred to. The inner surfaces of the sections 33, 34, are, of course, provided with suitable bristles 38.

A framework assuming the form of arcuate rods 39 is provided adjacent the yoke 15, the rods 39 being configurated substantially as shown and having the free end portions thereof secured in the aforementioned bearing blocks 16, as is best shown in the accompanying Figure 4. The rods 39 are adapted to support a suitable curtain 40, this being attached thereto by means of conventional hangers 41.

Finally, the invention includes a pair of atomizer assemblies designated generally by the reference character 42, each of the latter consisting of a tube 43, arcuated as shown and provided adjacent one end with a plurality of apertures 44. The tubes 43 are supported by suitable clamps or brackets 45 from the aforementioned yoke 15, and the remaining ends thereof are equipped with atomizer bulbs 46 of conventional design.

Suitable T-joints 47 are formed medially the length of the tubes 43, whereby a receptacle 48 may be separably connected to each of the tubes, as best shown in Figures 1 and 8. It will be noted that by compressing the bulbs 46, the contents of the associated receptacles 48 will be discharged through the apertures 44.

When the invention is placed in use, the apparatus is arranged substantially as shown in the accompanying drawings, and by simply manipulating the switch 21 to actuate the motor 20, the belt 29 together with the associated brushes 32 will be motivated as will be clearly understood. The brush assemblies 32 will be caused to submerge into the water 49 in the bath tub 25, and by progressively varying his position, the user may effectively cause the brushes to contact various portions of his body. It will be noted that by virtue of the articulate formation of the sections, 33, 34, and by the provision of the associated springs 37, the brushes will effectively adjust themselves to the contour of the user's body and an efficient contact thereof with the body will be facilitated.

The curtain 40 is provided for obvious reasons and one of the receptacles 48 may be filled with liquid soap, while the remaining receptacles may, if desired, contain toilet water. By simply compressing the associated bulbs 46, the contents of the respective receptacles will be discharged through the openings 44 onto the brushes 32, as has been already explained.

When the invention is not in use, the apparatus may be easily and quickly removed from the bath tub 25 by simply disconnecting the shaft sections 26, 27 as already set forth, and removing the standard 10 together with the associated belt assembly 29 from the tub.

It is believed that the advantages and use of the invention will be clearly understood from the foregoing disclosure and accordingly, further de-

scription thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. In association with a bathtub, a bathing apparatus comprising a roller removably and rotatively attached to the inner surfaces of the bathtub and extending transversely thereof, a base positioned at one side of said tub, a tubular standard extending upwardly from said base, a laterally angulated portion at the upper end of said standard, an inverted U-shaped yoke secured to said angulated portion, a further roller rotatively mounted in said yoke, said rollers being in alignment, a motor mounted on said base, a flexible shaft extending through said standard and operatively connecting said motor to the upper of said rollers, an endless belt engaging said rollers, a plurality of brushes secured to said belt at spaced intervals, said brushes comprising a mid-section and a plurality of end sections hingedly connected thereto, resilient means for normally urging said sections into a concave formation, a framework supported by said yoke, a curtain suspended from said framework, and a plurality of atomizers attached to said yoke and having nozzles positioned adjacent the said further roller for spraying toiletries within the tub.

2. In association with a bathtub, a bathing apparatus comprising a first roller removably and rotatively attached to inner surfaces of the tub and extending thereacross, a base disposed at one side of the tub, a standard extending upwardly from said base and having a laterally extending portion at the upper end of said standard, a yoke secured to said extending portion, a second roller rotatively mounted in said yoke in substantially parallel relationship with said first roller, a motor mounted on said base, a shaft drivingly connecting one of said rollers with said motor, an endless belt disposed on said rollers, a plurality of brushes secured to said belt at spaced intervals, said brushes including a mid-section and a plurality of end sections hingedly connected thereto, resilient means for normally urging said sections into a concave formation, and a plurality of atomizers attached to said yoke and having nozzles disposed adjacent said second roller for spraying toiletries within the tub.

WADE L. HACKER.
